UNITED STATES PATENT OFFICE.

MAURICE S. ROSENFELD, OF NEW YORK, N. Y., ASSIGNOR, BY MESNE ASSIGNMENTS, TO
JACOB SCHECHTER, OF NEW YORK, N. Y.

APPARATUS FOR CLEANING FILMS.

1,281,841.

Specification of Letters Patent. Patented Oct. 15, 1918.

Application filed May 14, 1915. Serial No. 28,121.

To all whom it may concern:

Be it known that I, MAURICE S. ROSENFELD, a citizen of the United States, residing in the borough of the Bronx, county of Bronx, city and State of New York, have invented a certain new and useful Apparatus for Cleaning Films, of which the following is a specification.

My invention relates to an apparatus for 10 cleaning motion picture films which in use become coated with oil from the projecting machine, small particles of carbon from the lamp, and dust.

The objects of my invention are to produce 15 a device in which foreign substances can be removed from the film in a rapid and efficient manner, and without injury to the film or the coating thereon.

These and further objects will more fully 20 appear in the following specification and accompanying drawings considered together or separately.

In the drawings in which the same parts 25 in all the figures are designated by similar reference characters,

Figure 1 is a plan view of the device;

Fig. 2 is a longitudinal section taken on the line 2—2 of Fig. 1; and

Fig. 3 is a transverse section taken on the 30 line 3—3 of Fig. 1.

In all the drawings, 1 represents a base plate on which is supported a trough 2 supported on a leg 3 and being provided at its bottom with a draw-off cock. The trough is 35 provided at one end with an idle roller 4, and at the opposite end with an idle roller 5. The roller 5 is preferably composed of soft rubber.

Extending from the back of the trough 40 is a pair of brackets 6, 6 to which is hinged a cover or lid 7. The cover is of a size to fit over the open top of the trough, and the brackets are of such a length that when the cover is thrown back, it will be entirely clear 45 of the trough. The cover is provided with a roller 8 corresponding in position to, and the surface of which engages with, the roller 4. At the other end of the cover is a soft rubber roller 9, which, when the cover is in 50 position, will engage the roller 5.

To one side of the cover is pivoted a lever 10, which is provided with a handle 11 and a lip 12. Projecting from one side of the trough is a lug 13, beneath which the lip 12

is adapted to engage, to lock the cover in 55 closed position on the trough.

Mounted on the base 1 is a standard 14, and pivoted at its center to the standard, is an arm 15. The upper end of the arm carries a sprocket wheel 16, which is driven 60 by means of a chain 17 from a source of power (not shown). The lower end of the arm 15 is engaged by a spring 18 which acts to yieldingly hold the sprocket wheel 16 against the pull of the chain. 65

Projecting from one end of the cover is a pair of bracket arms 19, 19, in which is journaled a shaft 20. The shaft carries a sprocket wheel 21 and a felt or other buffering wheel 22. 70

Carried in webs extending from the end of the trough 2 and integral with the base 1 is a stud 23, to which is pivoted an angle lever 24. One end of the lever 24 is bifurcated, and carries a shaft 25, on which is 75 mounted a buffering wheel 26 similar to the wheel 22 and which is in contact with the same, and a sprocket 21^a similar to sprocket 21. The chain 17 passes under the sprocket 21, around the sprocket 16, and over the 80 sprocket. This will cause the buffering wheels to rotate in the same direction. The tail of the angle lever is provided with a screw 27, which engages with a lug 28 on the base. By means of the screw the wheel 26 may be 85 brought into proper relation to the wheel 22.

Mounted in one side wall of the trough is a short shaft 29 carrying at its inner end an arm 30, the free end of which is bifurcated, and carries a roller 31. The outer end of 90 the shaft 29 is provided with a handle 32, the free extremity of which carries a spring pressed pin 33 which may engage with a shallow recess in the side of the trough to lock the handle in position. 95

Mounted on the base 1 adjacent to the buffering wheels 22, 26 is a standard which carries at its upper end a guide roller 34 on which the film rests.

The operation of the device is as follows: 100

The trough is partially filled with a solution which will loosen or remove the foreign matter which adheres to the film, and will not injure the film body nor the photographic coating thereon. The cover is 105 thrown back, and the arm 30 is raised. A film is led from a reel (not shown), passed over the roller 4, and dipped into the solu-

tion. The roller 31 is then lowered on to the film in the solution, to insure the film passing below the surface thereof. The end of the film is then laid on the roller 5, then 5 on the buffing wheel 26, next on the guide pulley 34, and finally secured to the shaft of a power driven take-up reel (not shown).

The power reel and the chain 17 are now put in operation, the film is drawn from 10 the supply reel and through the solution in the trough. The solution will loosen or remove the foreign substances from the film as it, the film, passes between the rollers 5 and 9, they will be rotated by contact with 15 the film, and will squeeze or squeegee the solution from the film. The film now passes between the buffing wheels 22 and 26 which are traveling at a high rate of speed. The buffing wheels will thoroughly dry the 20 film and polish its surfaces. The film is now wound upon the power driven reel, when it is in position to be used in a projecting machine, if a positive, or in a printing machine, if a negative.

25 In accordance with the provisions of the patent statutes, I have described the principle of my invention together with the apparatus, which I now consider to represent the best embodiment thereof, but I desire to have it understood that the apparatus shown is merely illustrative, and that 30

the invention can be carried out in other ways without departing from the spirit of my invention.

Having now described my invention, what 35 I claim as new and desire to secure by Letters Patent of the United States, is as follows:

1. A device of the character described, having a trough for carrying a cleansing 40 solution, smooth rollers on the trough, a cover, smooth rollers on the cover, a smooth guide roller carried on an arm pivoted in the trough, whereby a film may be passed between the rollers on the trough and cover 45 and under the guide roller.

2. A device of the character described, having a trough for carrying a cleansing solution, smooth rollers on the trough, a cover, 50 smooth rollers on the cover, a smooth guide roller carried on an arm pivoted in the trough, means for locking the guide roller in position, whereby a film may be passed between the rollers on the trough and cover and under the guide roller.

55 This specification signed and witnessed this 10th day of May, 1915.

MAURICE S. ROSENFELD.
